UNITED STATES PATENT OFFICE.

JOHN N. PETERSON, OF HAZELTON, NORTH DAKOTA.

COMPOUND TOOL.

No. 853,520.

Specification of Letters Patent.

Patented May 14, 1907.

Application filed July 23, 1906. Serial No. 327,388.

To all whom it may concern:

Be it known that I, JOHN N. PETERSON, a citizen of the United States, residing at Hazelton, in the county of Emmons and State of North Dakota, have invented certain new and useful Improvements in Compound Tools, of which the following is a specification, reference being had therein to the accompanying drawing.

This invention relates to improvements in combination tools and consists in the novel construction, combination and arrangement of devices hereinafter described and claimed.

The object of the invention is to provide a simple, strong and durable tool which may be effectively used as an adjustable alligator wrench for pipes, nuts, bolts and the like, a pair of pliers for pipes, wires, etc., a wire cutter and a screw-driver.

The above and other objects which will appear as the nature of the invention is better understood, are accomplished by the construction illustrated in the accompanying drawings, in which the same reference numerals indicate corresponding portions throughout, and in which,

Figure 1 is a side elevation of the improved tool; Fig. 2 is a similar view showing the jaws of the pliers locked in their closed position by the movable member or jaw of the adjustable alligator wrench; Fig. 3 is a detail longitudinal section through the alligator wrench, the parts being in the position shown in Fig. 2; Fig. 4 is a detail transverse section taken on the plane of the line 4—4 in Fig. 3; and Fig. 5 is a detail end elevation of the jaws of the pliers.

The tool comprises a handle or lever 1 which has one end shaped to form one member 2 of a pair of pliers 3 and its other end shaped to form the stationary member 4 of an adjustable alligator wrench 5. Pivoted at 6 on one side of the member 2 is a lever 7 which forms the other member of the pliers. Said members 2, 7 have their outer ends shaped to provide similar, opposing jaws 8 having their inner faces formed with transverse serrations and with the usual transverse, opposing, pipe or rod-receiving recesses 9 in which latter are also formed transverse serrations. As shown in Fig. 5, the inner faces of the jaws 8 are also formed with opposing, longitudinal grooves or recesses 10 in which may be held a wire, a nail or the like. The inner end of the lever or

member 7 is flattened and tapered, as shown at 11, so that it may be used as a screw-driver, and also to permit it to be wedged or clamped against the handle lever 1 by the adjustable member 12 of the alligator wrench 5, as shown in Fig. 2, for the purpose of retaining the jaws 8 of the pliers in their closed position. In order to permit the tool to be used for cutting wire, nails and the like, the two members or levers 2, 7 are formed adjacent to their pivot 6 with oppositely beveled cutting edges 13, 14, as clearly shown in Fig. 1. When the two levers 2, 7 are closed to the position shown in Fig. 2, said cutting edges 13, 14 cross each other and sever or shear a piece of wire or the like placed between them. The stationary member 4 of the alligator wrench is formed with an integral jaw 15 which projects angularly, as shown, and has upon its inner face serrations 16. Coacting with the stationary jaw 15 is an adjustable jaw 17 carried by the said member 12. The latter, as seen in Fig. 4, comprises a U-shaped plate 18 which receives the member 4 in its closed end and is adapted to slide upon said member. The opposite or open end of said U-shaped plate receives a reduced portion or shank 19 formed upon the jaw 17, said shank being secured between the two members of said plate by rivets 20, as shown. Formed on the inner edge of the member 4 are transversely-extending, angular ratchet teeth 21 adapted to be engaged by the teeth of a pawl 22 in the form of a block slidably mounted between the two members of the plate 18 and in a recess 23 formed in the inner edge of the shank 19. Said pawl carries a stem 24 which projects through and slides in a transverse opening in the shank 19 and has secured upon its outer end a finger-piece 25. The latter is in the form of a cross-bar and is adapted to seat in alining transverse grooves or recesses 26 formed in said shank and said plate. The pawl is held normally engaged with the ratchet teeth by a coil spring 27 surrounding the stem 24 and confined between said pawl and the bottom of a recess or seat 28 formed in the shank 19 concentric with the opening for said stem, as clearly shown in Fig. 4. The ends of the cross-bar or finger-piece 25 project slightly beyond the outer faces of the plate 18 and are milled or roughened to permit them to be readily grasped when it is desired to disengage the

pawl from the ratchet and adjust the jaw 17 upon the member 4.

From the foregoing description, taken in connection with the accompanying drawings, it is thought that the construction, uses and advantages of the invention will be readily understood without a more extended explanation.

Having thus described my said invention, 10 what I claim as new and desire to secure by Letters Patent of the United States, is

1. A wrench comprising a hand lever having a stationary jaw at one end, a ratchet upon the inner edge of said lever, a U-shaped 15 plate surrounding said lever and slidably thereon, a movable jaw having a reduced shank secured in the open end of said plate between its two members, said shank having a recess in its inner edge, a transverse 20 opening and a seat concentric with said opening and in communication with said recess, said shank and the members of said plate having alining recesses in their outer edges, a pawl block slidably mounted in the recess 25 in the inner edge of said shank, a stem carried by said pawl block and projecting through said opening, a cross-piece upon the outer end of said stem to seat in said alining re-

cesses in the outer edges of the shank and plate, and a coil spring upon said stem confined between said seat and said pawl for holding the latter normally engaged with said ratchet, substantially as described. 30

2. A tool of the character described comprising a handle having a plier jaw at one end and a stationary wrench jaw at its other end, a lever pivoted upon said handle and having at one end a plier jaw to co-act with the one upon said handle, the other end of said lever being formed with a bent, flattened 40 portion to engage one edge of said handle when the plier jaws are in their closed position, a loop slidably mounted upon said handle and adapted to fit over the bent flattened end of said lever to retain said plier 45 jaws in their closed position and a movable wrench jaw carried by said slidably loop and adapted to co-act with the stationary wrench jaw upon said handle, substantially as set forth. 50

In testimony whereof I hereunto affix my signature in presence of two witnesses.

JOHN N. PETERSON.
